UNITED STATES PATENT OFFICE.

FREDERIC L. THOMPSON, OF NEW BEDFORD, MASSACHUSETTS, ASSIGNOR
TO THE PAIRPOINT MANUFACTURING COMPANY, OF SAME PLACE.

DESIGN FOR A METALLIC PATTERN-STRIP.

SPECIFICATION forming part of Design No. 23,800, dated November 13, 1894.

Application filed January 18, 1893. Serial No. 468,867. Term of patent 7 years.

To all whom it may concern:

Be it known that I, FREDERIC L. THOMPSON, a citizen of the United States, residing at New Bedford, in the county of Bristol and State of Massachusetts, have invented and produced a new and original Design for a Metallic Pattern-Strip, of which the following is a specification, reference being had to the accompanying drawings, forming a part hereof, and showing 5 my pattern-strip in a plan view in Figure 1 and in side elevation in Fig. 2.

The leading feature of my design consists of scroll and leaf-work of the character and arrangement illustrated in the drawings, in 15 which the pattern-strip B consists of a shield b of irregular form surrounded by scrolls b',

and separated by irregular scroll-work b² from the conventionalized blossom b³, which is followed by the fanciful scroll b⁴, after which comes a shield b⁵ inclosed by scrolls b⁶, one of which terminates in a leaf b⁷, which is followed by a conventionalized blossom b⁸, which is in turn followed by a leaf-like scroll b⁹, which is separated from the shield b by a fanciful scroll-work b¹⁰. 25

What I claim is—

The design for a metallic pattern-strip herein shown and described.

FREDERIC L. THOMPSON.
